SHIPPER-LOCK FOR DRAWING-FRAMES.

SPECIFICATION forming part of Letters Patent No. 737,862, dated September 1, 1903.

Application filed December 26, 1902. Serial No. 136,543. (No model.)

To all whom it may concern:

Be it known that we, HENRY A. OWEN and OSCAR L. OWEN, citizens of the United States, residing at Whitinsville, in the county of 5 Worcester and State of Massachusetts, have invented a new and useful Improvement in Shipper-Locks for Drawing-Frames, of which the following is a specification.

This invention has reference to drawing-frames, and more particularly to improved mechanism in operative connection with the belt-shipper and casings or covers inclosing the draft and change gears.

In drawing-frames it is the usual practice 15 to inclose the gearing in hinged casings or covers, and the casings or covers may be opened by the operator to change or oil the gearing. To do this, the machine is stopped by throwing the belt onto the loose pulley by 20 operating the belt-shipper in the usual way, and the gear casings or covers are opened, giving the operator access to the gearing. Heretofore there has been great danger to the 25 operator in the starting of the machine by accident or other causes when the gear-casings were opened.

The object of our invention is to lock the belt-shipper with the belt on the loose pulley when the gear casings or covers are opened; 30 and the invention consists in the peculiar and novel construction of mechanism in operative connection with the belt-shipper and gear casings or covers for this purpose, as will be more fully described hereinafter 35 and pointed out in the claims.

Figure 1 is a side view of part of a drawing-frame, showing the fast and loose pulleys on the front roll-shaft, the belt-shipper, and shipper-bar and our improved mechanism 40 for locking the shipper when the gear-casings are opened. Fig. 2 is an end view of Fig. 1, partly in section, showing the hinged or pivoted gear-casings closed, the semicircular flanges on the pivots of the casings, the belt-shipper, and the arm and frame on the shipper-bar shaped to engage with the flanges on the gear-casings to lock the belt-shipper when the casings are opened, with the belt and pulleys 45 shown in broken lines. Fig. 3 is an enlarged 50 detail plan view showing the shipper-bar and

belt-shipper, the locking-arm forming a part of the shipper-fork and shaped to engage with the flange on the front gear-casing and the locking-frame secured to the shipper-bar in a position to engage with the flange on the 55 top casing.

In the drawings, *a* is the frame of the machine, supporting the fixed casing *a'* and the bearings for the front roll-shaft *a²*, with the fast pulley *a³* and the loose pulley *a⁴*. The 60 top gear-casing *b* is pivotally secured to the fixed casing *a'* and has the semicircular flange *b'* extending upward from the pivot, and the front gear-casing *c* is pivotally secured to the frame *a* by the bearing *c'* and has the 65 semicircular flange *c²* extending downward from its pivot. The shipper-bar *d* slides in the bearing *d'*, secured to the frame *a*, and carries the belt-shipper *d²* in a position to control the belt on the pulleys *a³* and *a⁴*. 70 The belt-shipper *d²* has the short arm *d³* and the locking-arm *d⁴*, forming the fork of the shipper. The locking-arm *d⁴* is extended inward and shaped to bring the L-shaped end *d⁵* into operative engagement with the flange 75 *c²* when the casing *c* is opened. On the shipper *d* is secured the upwardly-extending locking-frame *e* in a position to engage with the flange *b'* on the gear-casing *b* when the casing is opened. The gear-casings *b* and *c* 80 may be secured in their closed position by a spring-pin in the usual way.

In the operation of our improved shipper-lock for drawing-frames the belt-shipper is locked with the belt on the loose pulley by 85 the opening of either or both of the gear-casings by the operator. When the draft or change gears inclosed by the casings *b* and *c* require to be oiled or changed, the operator stops the machine by moving the shipper-bar 90 *d* outward, throwing the belt onto the loose pulley. The gear-casings *b* and *c* are now opened. The opening of the casing *b* in the direction of the arrow carries the flange *b'* downward and back of the locking-frame *e*, 95 and the opening of the casing *c* carries the flange *c²* upward and back of the L-shaped end *d⁵* of the locking-arm *d⁴* on the shipper, locking the shipper with the belt on the loose pulley. The shipper-bar *d* cannot be moved 100

inward to throw the belt onto the fast pulley until the gear-casings *b* and *c* are closed, thus eliminating all danger to the operator.

Having thus described our invention, we 5 claim as new and desire to secure by Letters Patent—

1. In a drawing-frame having gear-casings and a belt-shipper, mechanism intermediate the gear-casings and belt-shipper to lock the 10 belt-shipper by the opening of the gear-casings, for the purpose as described.

2. In a drawing-frame having gear-casings and a shipper-bar, a belt-shipper secured to the bar, an inwardly-extending locking-arm 15 on the bar, and a gear-casing provided with a projection to engage with the locking-arm to lock the shipper when the casing is opened, for the purpose as described.

3. In a drawing-frame having gear-casings 20 and a shipper-bar, a belt-shipper on the bar, an upwardly-extending locking-frame secured to the bar, and a gear-casing provided with a projection to engage with the locking-frame when the casing is opened to lock the shipper, for the purpose as described.

4. In a drawing-frame having a gear-casing pivoted to the frame of the machine, a shipper-bar and shipper, and an inwardly-extending locking-arm forming a part of the 30 shipper, said gear-casing having a flange to engage with the locking-arm on the shipper when the casing is opened to lock the shipper, as described.

5. In a drawing-frame, a gear-casing piv-

oted to a fixed casing, a shipper-bar and shipper, and an upwardly-extending locking-frame secured to the shipper-bar, there being a flange on the pivoted gear-casing to engage with the locking-frame on the shipper-bar when the casing is opened to lock the shipper, 40 as described.

6. In a drawing-frame having fast and loose pulleys, a fixed casing secured to the frame, the gear-casing *b* pivotally secured to the fixed casing and having the semicircular 45 flange *b'* on its pivot, the gear-casing *c* pivotally secured to the frame by the bearing *c'* and having the semicircular flange *c'* on its pivot, the shipper-bar *d* having the shipper *d²* with the arm *d³* and the locking-arm *d⁴* 50 with the L-shaped end *d⁵* to engage with the flange *c'* on the gear-casing *c*, and the upwardly-extending locking-frame *e* secured to the shipper-bar *d* to engage with the flange *b'* on the gear-casing *b* to lock the belt-shipper 55 with the belt on the loose pulley by the opening of the gear-casings and to unlock the belt-shipper when the gear-casings are closed, as described.

In testimony whereof we have signed our 60 names to this specification in the presence of two subscribing witnesses.

HENRY A. OWEN.
OSCAR L. OWEN.
